UNITED STATES PATENT OFFICE.

ALVARO S. KROTZ, OF JANESVILLE, WISCONSIN, ASSIGNOR, BY MESNE ASSIGNMENTS,
TO GENERAL MOTORS CORPORATION, A CORPORATION OF DELAWARE.

DOUBLE-ROW CULTIVATOR.

Application filed May 9, 1918. Serial No. 233,523.

To all whom it may concern:

Be it known that I, ALVARO S. KROTZ, a citizen of the United States of America, and resident of Janesville, Wisconsin, have 5 invented a certain new and useful Improvement in Double-Row Cultivators, of which the following is a specification.

The invention relates to cultivators in general, but more particularly to those 10 which are known as riding cultivators, being provided with wheels to support the frame which carries the cultivator gangs, and with a pole or tongue for a team of horses, so that the machine may be pulled 15 across the field to cultivate the corn, or other things usually planted in rows, and having means whereby the driver may control the machine and shift the gangs laterally to insure cultivation of the field of 20 corn, or other vegetation, in the proper or desired manner. Some cultivators of this general character are constructed for the purpose of cultivating one row at a time, being ordinarily known as single-row cul- 25 tivators, whereas other cultivators of this general class are larger and are constructed for the purpose of cultivating two rows at a time, and are known as double-row cul- 30 tivators. The invention, more specifically considered, relates to double-row cultivators of this general class.

The object of the invention, generally stated, is to provide a novel and improved construction whereby the cultivator-gangs 35 may be shifted or controlled by the swinging seat-rail, and whereby the individual gang-arches are each controllable independently of the seat-rail, and whereby pen- 40 dulums are advantageously employed to support the weight of the driver in the seat on the seat-rail, so that the machine may be steered to the right or left, and whereby the gang-arches may be controlled 45 at will, as will hereafter more fully appear.

It is also an object to provide certain details and features of construction and combinations tending to increase the general efficiency and desirability of a riding culti- 50 vator or wheeled cultivator of this particular construction.

To these and other useful ends the invention consists in matters set forth and

claimed and shown in the accompanying drawings in which—

Fig. 1 is a plan of a double-row cultivating machine, or two-row cultivator as they are sometimes called, embodying the principles of the invention.

Fig. 2 is a front elevation of said cultivating machine, showing the two poles or tongues in cross section.

Fig. 3 is a side elevation of the said cultivating machine, showing the near wheel removed.

Fig. 4 is a view similar to Fig. 1, but diagrammatic in character, and illustrating the control exercised over the wheels and the gang arches by the seat rail which is pivoted to swing laterally about a vertical axis provided by the pivot therefor at or near the center of the body-frame.

Fig. 5 is an enlarged detail sectional view, showing one of the pivotal connec- 75 tions.

Fig. 6 is an enlarged detail sectional view on line 6—6 in Fig. 2.

Fig. 7 is a still further enlarged detail sectional view of certain parts of the ma- 80 chine.

Fig. 8 is also an enlarged detail sectional view.

As thus illustrated, the invention com- 85 prises a body-frame comprising a trans- 90 verse member 1 to which the poles or tongues 2 are rigidly connected by oblique braces 3, there being a forwardly converging pair 95 of these braces for each pole or tongue, (see Figs. 1 and 4), the two poles or tongues being suitably spaced apart. The wheels 4 are carried on spindles 5, which latter have vertical portions 6 held in swivel bearings 7, the latter being rigidly connected by clamping devices 8 with the outer ends of the transverse frame-bar 1, so that this bar and the two wheel spindles form a sort of flat arch which is disposed a suitable distance from the ground, and whereby the two wheels may swing about the vertical axes to steer the machine to the right or to the left. For this purpose, forwardly ex- 100 tends arms 9 are rigidly secured to the wheel spindles, by means of the split clamp- 105 ing devices 10 which are removably clamped upon the curved lower portions of the spindles. The forward ends of these arms 9

are connected together by a transverse bar 11, the latter having its ends pivoted upon the ends of the arms 9, whereby the parallel motion connection is provided which 5 serves to keep the two wheels parallel. A pivot bolt 12 connects the longitudinally arranged seat-rail 13 with the cross-bar 1 of the body-frame, so that the seat at the rear end of said seat-rail may swing laterally. The forward portion of the seat-rail is connected by a pivot 14 with the bar 11, whereby lateral movement of the seat-rail will move the gangs 15 sidewise and skew the wheels about their individual steering axes, so that the machine will be steered to 10 the right or to the left.

With the construction shown, the cultivator gangs 15 are four in number, being arranged in pairs so that one pair is at one 15 side of the seat and the other pair at the other side thereof, said gangs being all arranged between the two wheels 4 of the cultivating machine. The two gang arches 16 are disposed in line with and below the 20 rear ends of the tongues 2, the out-turned or horizontal lower end portions of these arches being provided with long sleeves 17 upon which are adjustably mounted the clamping collars 18 which are provided on the forward ends of the cultivator-gangs. In this way the forward ends of the cultivator-gangs are adjustable laterally on the 25 sleeves 17, and when tightly secured in place on said sleeves the gangs are adapted to tilt upward at the rear ends, inasmuch as the sleeves 17 rotate on the horizontal portions of the gang-arches. By means of the adjustable collars 18 the distance between the 30 gangs of each arch can be changed or varied, in order to suit the requirements of different kinds of work, or different conditions. The outer ends of the gang-arches are connected by pendulum-rods 19 with the ears 20 on the castings or clamps 8, which are a part of the rigid body-frame, whereby the pendulum-rods 19 are adapted to swing sidewise at 35 their lower ends to permit lateral shifting of the cultivator-gangs, and so that these pendulum-rods serve as braces to resist the pull of the gangs while working in the ground. The body-frame also has a forward cross-bar 21 which is rigidly secured at 40 22 to the oblique bars 3 and at 23 to the rear ends of the tongues. Vertically disposed pendulum-rods 24 are pivoted at 45 25 on the end portions of the bar 21, so that these pendulum-rods swing laterally at their lower ends, and the lower ends of these rods are pivoted in ears 26 on collars 27 secured 50 to the outer ends of the gang-arches, these collars being also provided with ears 28 for the lower ends of the inclined pendulum-rods 19 previously described. The transverse upper portions of the gang-arches 16 55 are provided with castings or brackets 29

having means for loosely engaging the cross-bar 11, and with pivoted links 30 which have their other ends pivoted at 31 on the segment 32, which latter is pivoted at 14 to be turned about a vertical axis. This segment 70 75 is provided with holes 33 for the locking pin or bolt 34, which latter is inserted downward through a hole in the bar 11, so that the segment 32 can be locked in any rotated or adjusted portion thereof. When 80 segment 32 is rotated in one direction the gang-arches 16 will be pulled towards each other to reduce the distance between them, but when the segment 32 is rotated in the opposite direction the two gang arches will 85 be moved away from each other, thus increasing the distance between the two pairs of cultivator gangs, whereby the machine can be adjusted for rows of corn, for example, which are a certain distance apart in some 90 cases, and a greater or less distance apart in other cases. As previously explained, the gangs 15 can swing up and down, but do not swing sidewise, and consequently the shifting of the bar 11, when the seat is swung to either side by the driver, will cause the gang arches 16 to be shifted sidewise bodily, and this will shift the gangs themselves bodily 95 sidewise, as shown in Fig. 4.

The forward end of the seat-rail 13 is provided with a depending hook 35 upon which is fulcrumed a transverse bar 36, and the end portions of this bar are provided with holes 37 to receive the upper ends of the pendulum rods 38, which latter have their lower ends connected to the ears 39 on the previously mentioned collars 27, so that the upper ends of these rods turn about parallel longitudinal axes while the lower ends of said rods provide a common transverse axis of 100 relative movement. Thus the seat is maintained at the desired height and prevented from tilting downward by the upward pull of the forward end portion of the seat-rail 13 upon the rods 38, and this upward pull on the rods 38 is resisted, of course, by the rods 19 and 24, so that the latter serve 105 also to hold the forward end of the seat-rail down in position and to sustain the weight of the driver in the seat. Also, when the seat rail is swung laterally, the rods 38 swerve to one side and pull the gang-arches 16 with them, so that the lateral shifting of these gang-arches is caused in some measure by the swerving or side pull of the rods 38, which are some distance in advance of the bar 11, as well as by the endwise shifting movement of this bar 11 through its pivotal connection 14 with the seat-rail.

To raise and lower the cultivator gangs 15, a square shaft 40 is mounted transversely on the body-frame, in bearings 41, in such a manner that the shaft can rotate. The toothed segment 42 is rigid with the frame-bar 1, and its hand-lever 43 is rigid with the 125 130

shaft 40, being provided with a locking device 44, of the kind ordinarily employed on hand-levers, for engaging the teeth of the segment or curved rack. In this way, the 5 shaft 40 is normally locked against rotation. The hand-levers 45, however, are pivoted at 46 upon the curved racks or segments 47 which are fitted on the shaft 40, so that these racks on said shaft must rotate in unison when the shaft is rotated. Rods 48 connect the lower ends of the hand-levers 45 with their respective cultivator gangs, and these hand-levers have locking devices 49 to engage their respective racks or segments, 10 and with this arrangement, any hand lever 45, when released from its allotted rack or segment 47, can be employed for raising and lowering its allotted cultivator gang. On the other hand, when the hand-lever 43 is 15 released from its rack 42, this hand-lever can then be employed for rocking the shaft 40, and this will rock all of the segments 47, and therefore all of the hand-levers 45, with the result that all of the connecting rods 48 20 will be operated to raise or lower all of the gangs in unison. Thus the different cultivator-gangs can be raised and lowered individually, or in pairs, or all of them at the same time. It will be understood that any 25 suitable draft devices can be applied to the tongues 2, which latter are in the nature of parallel poles extending forward ahead of the machine, to which the horses are connected for pulling the machine forward 30 across the field. It will also be seen that a spring 50 is connected between the bar 21 and a downwardly extending arm 51 on the shaft 40, so that when this shaft 40 is rotated to raise all of the gangs at the same 35 time, the spring 50 will assist in so doing. It will be understood that the raising and lowering hand-lever devices thus provided are adjustable laterally (in any suitable known or approved manner) on the square 40 shaft 40, so that the distance between these hand-levers may be changed or varied in accordance with the distance between the cultivator-gangs. And with further respect 45 to this lateral adjustability of the cultivator-gangs, the transverse frame-bar 21 is preferably provided with holes 52 for the adjustment of the upper ends of the hanger-rods 24, so that the upper ends of the rods can be changed from one hole to the other when 50 the distance between the cultivator-gangs is changed.

60 In practice, it will be understood that the driver occupies the seat in position to place his feet in the stirrups 53 on the rear ends of the two inside cultivator-gangs. By pushing with his foot in either direction the seat will be swerved laterally in the other direction. And this will shift the cultivator 65 gangs 15 toward one of the wheels 4, each gang being moved bodily sidewise, as shown

in Fig. 4, and the lateral shifting of the gangs being always in a direction opposite to that of the lateral shifting of the driver's seat. The rows of corn, or other things, are not always straight, but sometimes swerve 70 suddenly to one side, and the cultivating machine shown and described is adapted to follow the rows, the lateral shifting of the cultivator-gangs bringing them over quickly when a sudden deflection in the rows is encountered, and the skewing of the wheels helping the situation by shifting the entire machine laterally. The driver will straighten up the machine as soon as the cultivator-gangs are again in correct or proper relation 75 to the rows, so that the rows of corn will be properly cultivated.

It will be understood, of course, that the cultivator-gangs 15 can be of any suitable known or approved character, such as those 80 ordinarily employed for cultivating corn or for similar purposes. The gangs can be adjusted laterally in the manner previously described, and it will be observed that the segment or pivoted element 32, through its connections 30 with the gang-arches 16, will always move the gangs an equal distance each side of the center pivot 14, so that the seat-rail 13 will always be midway between the two pairs of cultivator-gangs. Although the 85 tongues or poles 2 are rigid with the main body-frame, it will be seen that the gang-arches 16, while being adjustable laterally, are always at right angles to said tongues, and are always parallel with the cross-bar 90 of the main body-frame, inasmuch as these gang-arches have no skewing movement relatively to the body-frame. The various pendulum-rods 19 and 24, and the gang-arches 95 100 105 110 115 120 125 130 135 140 145 150 155 160 165 170 175 180 185 190 195 198 200 205 210 215 220 225 230 235 240 245 250 255 260 265 tion, after being skewed in either direction, just as a castor wheel tends to swing into line with the direction of travel. In this connection it will be seen that the pendulum rods 38 which support the front end of the gangs on the front end of the seat-rail 13, also have a tendency to swing back to normal position, after being swerved to one side. Consequently, after the driver has swung 10 the seat-rail 13 to one side, in order to dodge something on the ground, or in order to bring the cultivator into proper relation to the row of corn, the machine will then straighten itself automatically, and swing 15 the seat back to normal position, as soon as the driver discontinues the foot pressure on one of the gangs. By thus supporting the front ends of the gangs on the end of the seat-rail, so that the pendulums 38 will pull 20 the gangs laterally in either direction, the construction and mode of operation thus brought about tends to reduce the strain on other parts and has other advantages which will be understood by those familiar with 25 riding cultivators of this particular class. In addition, by arranging the steering axes a little ahead of the point where the wheel rests on a level ground surface, it will be seen that this brings the axes forward 30 enough to pass through the point of greatest pressure on the wheels, when the machine is traveling in soft ground, for in such case each wheel will then travel against a bank of earth, and with the steering axes disposed 35 at an angle in the manner shown, so that each axis enters a level ground surface a little in advance of a vertical line passing through the hub of the wheel, the machine will steer or turn to the right or left with 40 less effort. Thus the machine not only has a tendency to restore itself automatically to normal position, after being shifted to either side, by the lateral movement of the seat, but is also more easily handled and controlled. 45 The pendulum rods 19, it will be seen, are pivoted at their upper and lower ends to swing about axes which are disposed substantially at right angles to the inclined plane in which all of said rods swing laterally. 50 In this way, the rods do not bind at their ends when they swing to one side or the other, but move freely to permit the lateral shifting of the gangs previously described. Also, with this arrangement, the two gang 55 arches 16 are slidable toward and away from each other on the bar 11, which latter is transversely disposed, and movable endwise to control the steering wheels, as well as to shift the gang arches laterally when 60 the seat is swung to either side; and with the provision of the evener bar 36 previously mentioned, the weight of one gang arch tends to counterbalance the other, and the seat rail is in this way connected to the

lower ends of the gang arches as well as to 65 their upper ends.

With the construction shown and described, it will be observed that the seat rail 13, through the medium of the transverse bar 11, has an upper connection to the upper 70 ends of the two gang arches 16, and through the medium of the pendulum rods 38 is also connected to the lower ends of the two gang arches, and therefore to the front ends of the cultivator gangs. Each gang arch serves 75 to space apart the two cultivator gangs connected thereto, and through the medium of the gang arches the two pairs of cultivator gangs are properly spaced apart. The laterally swinging seat rail, therefore, has its 80 forward end so connected that it exerts a substantial control over both the upper end and the lower end of each gang arch, and in this way the cultivator gangs themselves are 85 easily controlled for the purpose of causing each gang to move sidewise bodily when conditions or circumstances require.

What I claim as my invention is:

1. A cultivating machine comprising 90 wheels, a body frame supported by said wheels, a pole or tongue rigid with said body frame, a cultivator gang, devices to support the gang on the body frame, so that the gang may be shifted bodily sidewise, and controlling means connected to the upper and lower ends of said devices to shift the gang bodily toward either wheel.

2. A structure as specified in claim 1, in combination with a similar gang, said devices including a gang-arch for the front 100 ends of said gangs, and means to connect the lower end as well as the top of said arch to said controlling means, with pendulum rods on the body frame to support 105 said gang-arch for sidewise movement and to maintain the gang-arch at right angles to said tongue.

3. A cultivating machine comprising a 110 main body frame, a tongue rigid with said body frame, wheels to support the body frame, a pair of cultivator gangs between said wheels, a gang-arch having its lower ends attached to the front ends of the cultivator gangs, pendulum rods supporting the gang-arch on the body frame, so that the gang-arch can swing laterally to shift the cultivator gangs bodily sidewise, a pivoted seat-rail, a seat on the rear end of said seat-rail, and a pendulum connection between the lower end of the gang-arch and the front 115 end of the seat-rail, whereby lateral movement of the seat-rail will shift the gang arch and cultivator gangs bodily toward 120 either wheel.

4. A cultivating machine comprising a 125 main body-frame, forwardly extending tongues rigid with said body-frame, supporting wheels, spindles to connect the

65

wheels with the body-frame, so that the wheels are adapted to skew about individual steering axes, arms extending forward from said spindles, a connecting bar between said arms, a seat-rail pivoted on the body-frame, a seat on the rear end of said seat-rail, a gang-arch at the rear end of each tongue, pendulum-rods connecting the forward end of the seat-rail with the adjacent lower ends of the gang-arches, so that the gang-arches counterbalance the weight of the driver, pendulum-rods supporting the gang-arches on the main body-frame, so that said arches are adapted to swing bodily 15 sidewise, and to maintain each gang-arch at right angles to its allotted tongue, mechanism on said cross-bar to adjust the distance between the gang-arches, and to connect the seat-rail with said cross-bar, and 20 cultivator-gangs having their forward ends connected to the lower end portions of the gang-arches.

5. A cultivating machine comprising a pair of gang-arches, cultivator-gangs connected to said gang-arches, means to support said gang-arches, an element mounted to rotate about a vertically disposed axis, links connecting the element with said gang-arches, so that partial rotation of said element will move the gang-arches toward or away from each other, means for locking said element in adjusted position, and means to shift said arches and element and links bodily to shift the gangs laterally.

35 6. A cultivating machine comprising a pivoted seat-rail, a seat on the rear end of said seat-rail, a pair of gang-arches supported for lateral movement, cultivator-gangs for said arches, a cross-bar on the forward end of said seat-rail, and pendulum-rods connecting the opposite end portions of said cross-bar with the lower ends of the gang-arches, so that lateral movement of the seat-rail about its pivot will 40 45 swerve the gang-arches and their gangs bodily sidewise in either direction.

7. A cultivating machine comprising a body frame supported by wheels, a pair of cultivator gangs, a gang-arch for the forward ends of said cultivator gangs, controlling means to shift the gang-arch bodily sidewise, means to connect said controlling means to the lower end of said gang arch, front pendulum rods depending from the 55 body frame to support the lower ends of the gang-arch and the front ends of the gangs on the body frame, and rear pendulum rods mounted to swing laterally in an inclined plane and extending downward 60 and forward from axes on the body frame to axes on the front ends of the gangs, to brace the lower ends of the gang-arch against the back pull of the cultivator gangs,

said axes all being at right angles to said inclined plane.

8. A structure as specified in claim 1, and mechanism connected to said means to skew said wheels about an individual steering axis for each wheel, when the gang is shifted laterally, said axes being disposed at such angles that the line of each axis is in advance of the lowest point of contact between the wheel and the ground surface, and so that the line of each axis will be substantially coincident with the point of greatest pressure on the wheels when the cultivator is traveling in soft ground.

9. A structure as specified in claim 6, in combination with steering wheels, mechanism to provide individual steering axes for said wheels, the line of each steering axis being disposed at an angle to enter the ground a distance in advance of the lowest point of contact between the wheel and the ground surface, and means to connect said mechanism with the seat-rail, so that both the pull of said pendulum-rods and the action of said wheels about their steering axes have a tendency to automatically return the seat-rail to normal position while the cultivator is moving forward.

10. A structure as specified in claim 7, said controlling means comprising a seat rail, and pendulum rod connection from the forward end of the seat-rail to the cultivator gangs, adapted to cause the seat-rail, after being swung to one side, to return of its own accord to normal position.

11. A cultivating machine comprising, in combination, a pivoted seat-rail, cultivator gangs, wheels to support and steer the cultivator, and devices for connecting the seat rail with said wheels and pendulum rods hung on the seat rail and connected at their lower ends to said gangs and thereby causing the seat-rail to return of its own accord to normal position after being swung to either side.

12. A structure as specified in claim 11, said devices comprising spindles for said wheels, means to support said spindles to turn about steering axes disposed at such an angle that the line of each axis passes into the ground in advance of the lowest point of contact between each wheel and the ground surface, and connections between the seat-rail and the cultivator-gangs.

13. In a cultivator, the combination of steering wheels, cultivator gangs, a gang arch, mechanism including a transversely arranged and endwise movable bar for controlling said wheels, means to connect said arch to said bar, so that endwise movement of the bar shifts the arch and the gangs laterally, a pole or tongue, a seat rail connected to said bar, pendulum rods hung on

the seat rail to control said gangs, a main frame rigid with said pole or tongue and supported by said wheels, pendulum rods to support the gang-arch on said frame, and 5 a pivot on said frame for said seat-rail.

14. A structure as specified in claim 13, in combination with a similar gang-arch connected to said bar, gangs for said additional arch, and pendulum rods to support 10 this arch on the frame, said means being adjustable to slide the two arches toward and away from each other on said bar.

15. A structure as specified in claim 13, and with the additional limitations of claim 15 14, in combination with pendulum rods to connect the forward end of the seat rail with the lower portion of said arches.

16. In a cultivator, the combination of 20 cultivator gangs, a gang arch for said gangs, a main frame, wheels for said frame, a seat rail pivoted on said frame, and means including a pendulum rod depending from the seat rail to support the gang arch.

17. A structure as specified in claim 16, 25 in combination with a similar gang arch, gangs for the arch, means including a pendulum rod depending from the seat rail to support the additional arch, and an evener bar on the end of the seat rail to support 30 said rods and whereby one arch tends to counterbalance the other.

18. In a cultivator, the combination of a 35 wheeled body frame, cultivator gangs, means to support the gangs on the body frame, having provisions to permit each gang to move bodily sidewise, a seat rail pivoted to swing laterally on the body frame, and pendulum rods extending down-

ward from the forward end of the seat rail 40 to control said gangs.

19. In a cultivator, a gang arch, cultivator gangs for said gang arch, a wheeled body frame, a laterally swinging seat rail, a connection between the seat rail and the upper end of the gang arch, and a connection 45 between the seat rail and the lower end of the gang arch.

20. A structure as specified in claim 19, in combination with devices controlled by the upper connection between the seat rail 50 and gang arch to control the wheels of the body frame.

21. In a cultivator, the combination of a wheeled body frame, a pair of gang arches, a pair of cultivator gangs for each gang 55 arch, a laterally swinging seat rail on the body frame, an upper connection between the seat rail and said gang arches, a connection from the seat rail to the lower end of one gang arch, a connection from the 60 seat rail to the lower end of the other gang arch, swinging connections extending from the body frame to one gang arch, swinging connections extending from the body frame to the other gang arch, and means controlled by said upper connection to control the wheels of the body frame.

22. A structure as specified in claim 21, in combination with means on said upper connection to vary the distance between the 70 two gang arches, thereby to vary the distance between one pair of cultivator gangs and the other pair of cultivator gangs.

Signed by me at Janesville, Wis., this 16th day of April, 1918.

ALVARO S. KROTZ
